UNITED STATES PATENT OFFICE.

EMANUEL INGHAM, OF SAN DIEGO, CALIFORNIA.

MEANS FOR PRODUCING TUBULAR FABRICS.

1,403,785.

Specification of Letters Patent. Patented Jan. 17, 1922.

Application filed March 27, 1919. Serial No. 285,573.

To all whom it may concern:

Be it known that I, EMANUEL INGHAM, a subject of the King of Great Britain, residing at San Diego, in the county of San Diego and State of California, have invented certain new and useful Improvements in Means for Producing Tubular Fabrics, of which the following is a specification.

This invention relates to means for weaving tubular fabrics and has special utility when applied to the weaving of such fabrics from coarse, heavy material such as is employed in the production of sacking.

This invention is in the nature of a further development of that covered by my prior Patent No. 1,328,794, dated January 20, 1920, and copending application Serial Number 279,511 filed February 27, 1919.

While the apparatus disclosed in the above mentioned patent and application is intended for use in producing curved fabrics, U-shaped in cross section, the present invention contemplates the provision of means for producing a complete tubular fabric in indefinite lengths. The invention consists therefore in so supporting the parts of the mechanism as to permit of a closed tubular fabric, formed in accordance with my above mentioned application, to be continuously removed from the machine without the necessity for cutting the same.

In order that the invention may be readily understood reference is had to the accompanying drawings forming part of this specification and in which:

Fig. 1 is a side elevation of my improved machine showing means for supporting the needle and associated parts so that the completed tubular fabric may be continuously removed;

Fig. 2 is a central longitudinal section on an enlarged scale showing my improved means for supporting the needle and associated parts;

Fig. 3 is a plan view of the needle and form shown in Fig. 2;

Fig. 4 is a front view of such form;

Fig. 5 is a fragmentary detail illustrating my improved thread guide;

Fig. 6 is an enlarged vertical section through the upper end of such guide;

Fig. 7 is a transverse section on the line 7-7 of Fig. 1, looking in the direction of the arrow;

Fig. 8 is a sectional plan view through some of the parts shown in Fig. 7;

Fig. 9 is a fragmentary, sectional side elevation of parts of the mechanism shown in Figs. 7 and 8;

Fig. 10 is a perspective view showing the appearance of the tubular fabric as it leaves the machine;

Fig. 11 is a transverse section on the line 11-11 of Fig. 1;

Fig. 12 is a fragmentary, vertical, longitudinal section through part of the supporting frame; and

Fig. 13 is a sectional plan view of the machine substantially on the line 13-13 of Fig. 1.

Referring to the drawings in detail, the machine is mounted on a suitable base 1. Adjacent one end of this base is secured an upright framework consisting of pedestals 2 united by webs 2^a, and adjacent the other end of the base 1 is mounted a pedestal 3. A main shaft 4 is journaled in suitable bearings in the pedestals 2 and 3 and carries at one end a pulley 5 to which power may be applied for driving the machine. To the shaft 4 is secured a pair of mutilated beveled gears 6 and 7 which mesh with a beveled pinion 8 secured to the lower end of a short vertical shaft 11 carrying at its upper end a beveled pinion 9 which meshes with a similar pinion 10 secured to a sleeve hereinafter described.

A fixed rigid arm or shaft 12 is securely clamped at its rear end in split sockets 13 carried at the upper ends of the pedestals 2, and such shaft extends forwardly nearly the full length of the machine thus constituting a cantilever structure.

Journaled on this shaft 12 is a sleeve 14 having a rear portion 14^a to which the pinion 10 is rigidly secured, the section 14^a being united with the section 14 by means of a longitudinal separable coupling 13^a. At its forward end the sleeve 14 carries a circular oscillatory needle 15 similar in all respects to the needle shown in detail in my prior applications.

A grooved collar 16 is secured to the sleeve 14 and in the groove of such collar works the bifurcated end of a lever 17 pivoted at 18 to a fixed bracket and having its depending lower end 19 engaging a cam grooved in a cam member 20 which is secured to the shaft 4.

The end of the shaft 12 projects forwardly beyond the needle 15 and on such forwardly projecting end is rigidly mounted

the form around which the fabric is woven. This form consists of a circular ring or disc 21 clamped to the shaft by means of a set screw 22. This ring is disposed adjacent to the needle as clearly shown in Fig. 2 and is of substantially the same diameter. It constitutes the foundation around which the weft thread is laid by the needle and encloses the loop-interlocking mechanism.

10 This mechanism is identical with that shown in detail in Figs. 19 to 24 of my co-pending application Serial No. 279,511, and comprises, as its essential feature, a reciprocating hook 15^a, operated by a pair of cams 15^b, and projecting slightly beyond the periphery of the ring 21. This hook serves to catch the loops of weft thread and interlock them to form a continuous seam, as fully described in said above mentioned application. In the present instance, however, the cams 15^b are mounted on the sleeve 14, since the shaft 12 is fixed, and does not turn. Secured to the extreme forward end of the shaft 12 is an elongated block 23 held by means of a set screw 24 and preferably having rounded ends as indicated at 27 in Fig. 4. Supported by the ring 21 and block 23 is the body 25 of the form, preferably consisting of sheet metal. By reference to the drawing it will be readily understood that this body when in position is circular at the rear end and flattened and elongated laterally at its front end giving rise to the configuration shown in Figs. 3 and 4.

35 A short tubular thread guide 28 of suitable shape is secured to the needle and the weft thread 23 passes to the needle through this tube from the flared mouth 29 of a thread guide 31, the upper end 30 of which is preferably swiveled as indicated in Fig. 6. It will be understood that as the needle oscillates, the swiveled end 30 of the thread guide swings from side to side as may be required to properly accommodate the pull of 40 the thread. The weft thread 33 enters the lower end of the guide tube 31 from a fixed reel 32 as shown in Fig. 1.

34 designates the warp threads which, as in my prior application Serial Number 50 279,511 pass through a tension device 36 and a heddle mechanism 37, such threads being fed from fixed reels (not shown).

55 The heddle mechanism is operated as in said prior application by means of ratchet mechanism 39 actuated by a cam 40 on the shaft 4. The tension and heddle mechanisms which are entirely free from the arm 12 each comprise two separable halves and are supported on pedestals 36^a-36^b and 37^a-37^b, respectively. The sections of the tension mechanism pedestals are adapted to slide in an arc-shaped groove 42 and the sections of the heddle mechanism pedestals are adapted to slide in an arc-shaped groove 43, these 60 grooves being formed in a suitable support-

ing table 41 and being struck from a common center. This center is the pivot pin 45 shown in Fig. 13 on which pin is pivoted a pair of operating handles 44 which are suitably connected to the sections of the tension and heddle mechanisms as described in my prior application.

It will be understood that as the fabric 35 is woven by the oscillating needle 15 around the form 25 it is drawn off of the 75 front end of such form by means of the take-up mechanism now to be described. Referring particularly to Figs. 1, 7 and 8, it will be seen that this take-up mechanism comprises a guide roller 46, over which the 80 fabric passes, such guide roller being supported near the upper end of a pair of standards 47. Also journaled in these standards is a take-up roller 48 on which the fabric is wound as indicated in Fig. 1. The 85 roller 48 has secured to one end a gear 49 which is operatively connected to a similar gear 51 by means of an intermediate pinion 50. This construction renders it possible to vary the speed of the roller 48 by taking off 90 two of the gears and substituting others of different relative diameters. The gear 51 is journaled on a stud carried by one of the standards 47 and has formed integrally therewith a ratchet wheel 52. This is adapted to be engaged by a pawl 53 pivoted to a reciprocating block 54 suitably mounted in guideways in the standard 47 and actuated by means of a lever 55 pivoted at 56 and caused to vibrate by means of a cam 58 secured to the shaft 4. The end of the lever 55 is preferably rounded as shown at 55^a in Fig. 9 and fits into a notch or pocket in the block 54. The lever is actuated in one direction by means of a spring 57. A locking pawl 59 pivoted to the standard 47 and urged against the ratchet 52 by means of a spring 60 serves to prevent backward rotation of the take-up roll 48.

Fig. 10 shows the appearance of the tubular fabric as it leaves the machine. This fabric is designated in its entirety by the reference numeral 35 and has on its under side a longitudinal seam 35^a formed by the interlocking of the loops of weft thread as 115 described in my prior application Serial Number 279,511.

What I claim is:

1. The combination with a curved form, of a cantilever arm for supporting the same, 120 means for placing warp threads around said form, and means for weaving weft thread across the warp and around said form, said weaving means being wholly supported on said arm.
2. The combination with a curved form, means for supporting warp threads there-around, and an oscillatory needle for laying weft threads across the warp, of a rigid arm, supported at one end only, by which 130

said form and needle are both wholly carried.

3. The combination with a rigid arm, of a circular weft needle mounted for oscillation thereon, and a warp supporting form associated with said needle and carried wholly by said arm.

4. The combination with a fixed shaft, of a sleeve surrounding said shaft, an oscillatory weft needle secured to said sleeve, and a warp supporting form carried by said shaft adjacent the needle.

5. The combination with a curved form, of means for supporting warp threads there-around, an oscillatory needle adapted to lay weft thread across the warp, a supporting shaft, a sleeve surrounding said shaft, to which sleeve the needle is rigidly secured, and means for actuating the said sleeve to oscillate the needle.

6. The combination with a curved form, of means for supporting warp threads there-around, an oscillatory needle adapted to lay weft thread across the warp, a supporting shaft, a sleeve surrounding said shaft, to which sleeve the needle is rigidly secured, and means for imparting both an oscillatory and an axial movement to said sleeve.

7. The combination with means for supporting warp threads, of an oscillatory circular needle adapted to lay weft thread across the same, and a fixed thread guide having its mouth disposed adjacent the nee-

dle and adapted to deliver weft thread thereto.

8. The combination with means for supporting warp threads, of an oscillatory needle adapted to lay weft thread across the same, of a fixed thread guide having its mouth disposed adjacent the needle and adapted to deliver weft thread thereto, said thread guide having its end swiveled so that it may swing from side to side as the needle oscillates.

9. The combination with a curved form and means including a circular oscillatory needle for weaving a tubular fabric there-around, of take-up mechanism adapted to draw such fabric from the form as it is woven, said mechanism comprising a take-up roller and pawl and ratchet mechanism for operating the same.

10. The combination with an elongated curved form, substantially circular at one end, of an arm extending axially from the center of such end of said form for wholly supporting the same, means supported by said arm for laying threads around the said circular end of said form and uniting them to produce a complete tubular fabric, and means for drawing the finished fabric along said form and off the other end thereof, as it is produced.

In testimony whereof I affix my signature.

EMANUEL INGHAM.
